UNITED STATES PATENT OFFICE.

WALTER W. RIEDEL, OF DAYTON, OHIO, ASSIGNOR, BY MESNE ASSIGNMENTS, TO DELCO-REMY CORPORATION, OF DAYTON, OHIO, A CORPORATION OF DELAWARE.

ENGINE-STARTING APPARATUS.

Application filed August 1, 1925. Serial No. 47,427.

This invention relates to improvements in engine starting devices and particularly to starting devices for motor-vehicle engines, in which the power-transmitting member is normally held out of engagement with the engine, but which may bodily be moved into engine-engaging position by causing it to rotate.

It is among the objects of the present invention to provide an engine starting device including a motor capable of being moved bodily to engage the engine, but which is so supported that it will be held positively out of engine-engaging position while the engine is self-operating, thus substantially eliminating the possibility of road shocks on the vehicle throwing the motor into engagement with the engine.

Another object is to so construct and arrange the motor-supporting means that the member which holds the motor out of engine-engaging position, while the engine is self-operating, will also function to cause the motor to be moved bodily into engine-engaging position when the motor is rotated.

Further objects and advantages of the present invention will be apparent from the following description, reference being had to the accompanying drawings, wherein a preferred form of the present invention is clearly shown.

In the drawings:

Fig. 1 is a fragmentary plan view showing a portion of the engine and flywheel, and a part of the starting motor including its power-transmitting member and the detent associated therewith;

Fig. 2 is a front end view of the device illustrated in Fig. 1; and

Fig. 3 is a diagrammatic view showing the various elements and their respective electrical connections.

Referring to the drawings, the numeral 20 designates an internal-combustion engine, a portion of which is shown in Fig. 1. 21 designates the engine flywheel provided with a V-shaped peripheral groove 22. The numeral 23 designates any suitable projection formed on the crankcase of the engine and upon which the starting motor mechanism is supported.

The starting motor referred to by the numeral 24 comprises a frame having projecting ears 25 which are pivotally secured to a standard 26, by means of pin 27. The standard 26 is secured to the crankcase projection 23 by means of bolts 28. The motor is provided with an armature shaft 29 to which is secured the power-transmitting member 30. This power-transmitting member comprises any suitable friction disc carried by a collar 31 which fits on shaft 29 and is secured thereto by means of the screw pin 32. The edge of the friction disc 30 is formed to fit into the V-shaped peripheral groove 22 on flywheel 21, so that rotation of the disc will grip the flywheel and rotate it.

Another standard 35 is secured to the crankcase projection 23 adjacent the standard 26. A pin 36 is carried by said standard, said pin pivotally supporting the detent 37. This detent has a curved surface 38 which is adapted to engage with and fit about a portion of the power-transmitting element 30, when the motor 24 is in its inoperative or engine-disconnected position, as shown in Fig. 2. The remaining portion of this curved surface 38 is of such a curvature that it will remain in engagement with the power-transmitting element 30, as the motor 24 moves radially about its pivot pin 27. The detent terminates at a point approximately in the vertical plane passing through the center of the pin 27. This end of the detent is provided with an angular surface 39, as shown in Fig. 2. On the hub portion of the detent 37 which surrounds the pin 36, there is provided an extension 40, to which is secured one end of the tension spring 41, the opposite end of said spring being secured to a screw 42 fastened to the crankcase projection 23. This spring 41 tends to hold the curved surface 38 of the detent in tight engagement with the power-transmitting element 30 of the motor, as it moves radially about the pin 27.

Referring now to the diagrammatic Fig. 3, the numeral 50 designates a storage battery, 51 the motor starting switch, 52 the field of the starting motor 24, 53 the starting-motor-circuit contact, 54 the cooperating starting-motor-circuit contact and 55 the

armature of the relay. 56 designates the generator having a field 57. Numeral 58 designates the generator contact of the relay, 59 the core and 60 the winding of the 5 relay.

The operation of the device is as follows: When the engine is inoperative and the starting motor is not rotating, said motor will be in the position as shown in Fig. 2; 10 being securely held in this position by means of coil spring 41 exerting a pull upon the extension 40 of the detent, causing said detent to be pressed against the power-transmitting element of the motor. This pressure of said detent on the motor element will prevent said element from being thrown toward the flywheel 21 of the engine, due to any road shocks of the motor vehicle.

When the operator wishes to crank the 20 engine, the starting pedal 51 is depressed, thereby permitting current to flow from the storage battery 50 through the motor field 52, across the armature of the motor 24, to the motor contact 53, thence to its cooperating 25 contact 54 which is held in engagement with the contact 53 by means of springs 62 connected with the armature 55. From contact 54 current will flow through the armature 55 back to the battery via the ground connection. This will cause the power-transmitting 30 member of the motor 24 to rotate in a counterclockwise direction, as regards Fig. 2. Rotation of the power-transmitting element in this counterclockwise direction 35 will cause it to travel along the curved surface 38 of the detent toward the engine. As soon as the motor reaches a point past the plane passing through the center of the pivot pin 27 of the motor 24, the motor will, of 40 its own weight, move toward the engine flywheel and cause the engagement of its power-transmitting member 30 with the engine flywheel 21. Thus it will be seen that the motor is bodily moved from its inoperative 45 into its engine-engaging position. Rotation of the power-transmitting member 30 will, when said member engages the flywheel, and due to its angular position relative to the center of the flywheel tend to wedge said member into frictional engagement with the flywheel, thus tending to rotate the flywheel in a clockwise direction, to crank the engine. While the motor cranks the engine detent 37 is moved into the position 37^a by the spring 50 41. Motion in this direction is limited by a lug 43 on the hub of detent 37 striking a stop 44 on standard 35.

As soon as the engine becomes self-operating, the rotation of the flywheel will tend 60 to kick the power-transmitting member 30 out of engagement therewith, consequently throwing the motor bodily about its pivot point 27 toward the detent 37. The member will first engage the angular surface 39

of said detent and then force its way slidably 65 along the curved path 38 into a position as shown in Fig. 2 in which the detent acting under the force of the spring 49 will maintain the said member while the motor is inoperative. 70

Self-operation of the engine will cause the generator 56 to supply current for charging the battery 50. Thus current will flow from the generator through wire 63 to wire 64, through the coil 60 about the core 59 of the 75 relay and back to the generator via the wire 65. This will energize the core 59 and cause it to attract the armature 55 against the operation of the spring 62. Movement of the armature toward the core 59 will move 80 the contact 54 out of engagement with the motor contact 53 and bring the armature 55 into engagement with the generator contact 58. Now, the generator will deliver current through the wire 63 to the battery 50 and via the ground connection to the armature 55, thence through the contact 58 back to the generator via the wire 65 and thus charge the battery. While this charging of the battery is in effect, it may be seen that the motor circuit is broken at the contact 53, so that even though the operator maintains pressure on the switch 51 to close the circuit at this point, the motor will cease to operate soon after the engine becomes self-operative. 85 90

While the form of embodiment of the invention as herein disclosed, constitutes a preferred form, it is to be understood that other forms might be adopted, all coming within the scope of the claims which follow. 100

What is claimed is as follows:

1. A starting device for an internal combustion engine including a flywheel, comprising, in combination, a motor pivotally supported at the side of the engine flywheel and normally inclined with respect to its pivotal point away from said engine flywheel, said motor having a drive shaft and a power-transmitting member thereon and a circular track spring-pressed into direct engagement with the power-transmitting member along which said member is adapted to roll when said motor is operated, until the motor is moved bodily beyond the vertical plane passing through the pivotal point 115 thereof.

2. A starting device for an internal combustion engine including a flywheel, comprising, in combination, an electric starting motor having an armature shaft upon which is mounted a power-transmitting member, a pivotal support for said motor upon which the motor is normally carried in a position inclined from the engine, and a circular track spring-pressed into engagement with the power-transmitting member, and including a portion normally holding the motor in said inclined position while the motor is inoper- 125

ative, said track being substantially concentric with the pivot point of the motor and extending beyond the vertical plane passing through said pivot point, and providing a 5 run-way for the power-transmitting member whereby, when the motor is operated, said power-transmitting member will roll

along said track to move the motor circumferentially about its pivot point to cause engagement of the power-transmitting member with the engine flywheel. 10

In testimony whereof I hereto affix my signature.

WALTER W. RIEDEL.
